APPARATUS FOR DRYING FOUNDRY MOLDS

Charles A. Barnett and Joseph M. Beyvl, Cleveland, Ohio, assignors to The Foundry Equipment Company, Cleveland, Ohio, a corporation of Ohio

Application July 13, 1943, Serial No. 494,458

2 Claims. (Cl. 22—87)

1

The present invention relates to apparatus for conditioning foundry molds and the like and has particular reference to the backing and drying of the green sand in such molds in a zone adjacent the mold-forming surface thereof.

In metal founding practice, after the green sand is so patterned or formed in the mold body or flask (the latter of course including cores and drags, if need be), the sand must be so treated or conditioned as to be enabled to come in contact with the molten metal without causing certain disadvantageous results. Green sand molds have therefore previously been treated or conditioned by either one of two general methods. One of these methods is the surface or skin drying process whereby heat is applied to the mold-forming surface of the sand, such as by a gas torch played over such surface, or by heat radiated from a gas, oil, electrical or solid fuel burner. The other method generally employed to condition green sand molds involves the subjecting of the entire mold body to a baking or heat soaking operation in a drying oven. It will readily be appreciated that the first of these two general methods of treatment is subject to the disadvantage of uneven application of heat to the mold-forming surface and the inefficient and uneconomical transmission of heat; the second general process having the disadvantage of requiring relatively long periods of time for effecting the penetration of the drying or baking heat throughout the entire mass of the mold body, not to mention the excessive amount of heat required.

In the co-pending U. S. patent application of C. A. Barnett, co-applicant herein, Serial No. 408,063, filed August 23, 1941, now Patent 2,385,962, there has been disclosed a mold conditioning process and apparatus wherein the mold body, containing the green sand, is placed subjected to a blast of heated air which is so directed as to impinge uniformly upon the sand mold-forming surface, producing rapid and uniform drying of such surface throughout an even depth zone. However, it is not feasible or practical to employ a continuous conveyor for all types and sizes of foundry molds. Either the space required by such a conveyor and its associated housing and forced air heating apparatus would be too large when considered in proportion with the number or sizes of the molds conditioned, or the cost of such an apparatus would be out of proportion.

Our present invention, therefore, is directed to the provision of an apparatus for conditioning and drying sand molds which are of such a size and weight as to prevent them from practically and economically being transported upon a continuous conveyor type of drying oven, and wherein the mold body itself is utilized as part of an enclosing housing or drying oven during the green

2

sand drying and baking operation. Briefly outlined, our invention comprises an open-topped housing which is adapted to support the mold body upon its top edge, together with a forced air heating source located adjacent the open-topped housing and adapted to deliver a mass of heated air through a plurality of appropriately directed nozzles against the mold-forming sand surface.

10 Additional objects and advantages of the invention shall become apparent as the following description proceeds.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a top plan view of a single mold drying apparatus embodying the principle of our invention;

Fig. 2 is an elevational view, partially in section, of the apparatus shown in Fig. 1;

Fig. 3 is an enlarged, sectional detail of the sand seal around the top edge of the supporting housing of the apparatus shown in Figs. 1 and 2;

Fig. 4 is a top plan view of a multiple mold drying apparatus embodying the principle of our invention;

Fig. 5 is a vertical sectional view taken substantially along the line 5—5 and in the direction of the arrows, in Fig. 4;

Fig. 6 is a vertical sectional view taken substantially along line 6—6 of Fig. 4;

Fig. 7 is a top plan view of a multiple mold drying apparatus, whose construction has been so modified as to accommodate the interior part of a mold body or core, and embodying the principle of our invention;

Fig. 8 is a vertical sectional view taken substantially along the line 8—8 of Fig. 7; and

Fig. 9 is a vertical sectional view taken substantially along line 9—9 of Fig. 7.

Now referring more particularly to Figs. 1 and 2, the apparatus shown therein comprises an open-topped housing indicated generally at 1 with a foundry mold body supported upon the top side thereof in inverted position. A heater 3, consisting of a heat transfer chamber and a burner for gas, oil or solid fuel (steam or electrical heat energy may be utilized if commercially feasible) is connected to the centrifugal blower 4 which in turn delivers the heated air or like gaseous medium to the supply or delivery conduit 5 leading to the interior of the space

enclosed by the housing 1 and the inverted mold body 2. A return or recirculating duct 6 leads from interior of the housing 1 back to the intake side of the heater 3.

This structure is operative with or without an outside vent in the system for the recirculated air. There is adequate air in the system to absorb the moisture in one or a few molds. The absorptive capacity of the air is much greater than required and is not approached in normal operation, the limiting factor being the expansion of the air due to moisture absorption, and with some types of heaters, the addition of medium such as combustion products. This latter limiting factor is not reached in drying the single mold and when the mold is dried and removed, any pressure due to expansion is relieved and fresh air is admitted into the system between the time of removal of the dried mold and the placing of a new mold on the open top housing, thus venting the system.

If desired, the mold may be vented for bleeding out any air or excess products, for example, as pointed out in my copending application, Serial No. 494,756, filed July 15, 1943, now Patent 2,417,673, granted March 18, 1947, by providing a suitable venting duct in the return duct 6. The venting duct may be utilized for withdrawing the excess air from the interior of the mold.

The housing 1 consists of the bottom wall 7 and the vertical side walls 8 and 9. These walls are primarily fabricated of brick, concrete or other equivalent insulating material in order to minimize heat loss. Supporting piers 10, consisting of vertically mounted I-beams, are located at each of the four corners of the rectangular shaped housing 1, and in addition to reenforcing the side walls 8 and 9, also provide bearing supports for the weight of the mold body 2. The latter comprises the outer casing or flask 11 and the interior filling of mold sand which forms the mold cavity indicated at 12.

A plurality of nozzles 13 and 14 are located on the outlet end of the conduit 5, and as shown in Fig. 2, are directed both upwardly and outwardly toward the surface of the mold cavity 12 whereby the mass of heated air supplied from the heater 3 and blower 4 is propelled or forcibly projected substantially at right angles all over, and uniformly against, the interior surface of the sand mold, drying and baking the latter to a uniform depth adjacent such mold-forming surface. The arrows in Fig. 2 substantially indicate the manner in which the heated air streams from the nozzles 13 and 14 impinges against the surface of the mold cavity 12. After such impingement and transfer of the majority of the sensible heat from such impinging air streams to the surface and adjacent surface zone of the sand in the mold body 2, the body of air then passes into the outlet openings 15 in the recirculating duct 6, whence the cycle of reheating in the heater 3, blower 4 (driven by the drive motor 16) through the delivery conduit 5 to the housing 1, continues. As best shown in Fig. 3, the mold body 2 is mounted upon the top edge of the housing 1 in such manner as to provide an effective air seal, preventing escape of the heated air to the atmosphere. This sealing means comprises a channel 17 located around the top sides of the housing walls 8 and 9 and slightly wider than the bottom marginal flange 18 on the flask 11. The channel 17 is filled with sand which contacts the bottom side of the flange 18 and forms an effective air seal between the channel 17 and flange 18.

The above described apparatus has been found to be extremely efficient in solving the problem of satisfactorily and rapidly drying green sand in foundry molds which, although they can be handled or transported from one place to the other by means of overhead cranes or hoists, cannot be practically or economically handled on a continuous conveyor. Our above described invention is particularly well adapted to the drying of foundry molds of about 50 to 100 square feet cross sectional dimensions. From the foregoing description, it will be readily appreciated that the apparatus embodying our invention not only overcomes the problem of conveying molds of this size for the purpose of efficiently projecting a uniformly drying mass of heated air against their mold cavities, but also eliminates the necessity of a relatively large and cumbersome enclosing housing, inasmuch as the mold body itself is so combined with the supporting housing 1 as to form a complete and enclosed space for the reception and recirculation of the drying air mass.

In Figs. 4, 5 and 6, we have illustrated the principle of our invention as applied to a multiple mold drying apparatus. The latter comprises an elongated housing indicated generally at 20 having the vertical side walls 21 and the vertical end walls 22, enclosed on the bottom by the bottom wall 23. The elongated housing 20 is divided into a series of four adjacent compartments by means of the transverse walls 24. The walls 21, 22, 23 and 24 are of course fabricated from an insulating material.

Supporting piers 25, consisting of vertical I-beams, are located at each of the four corners of the four compartments in the housing 20 and have bearing plates 26 positioned upon their top ends to receive the inverted mold bodies 30. Sand seals, comprising the channels 27 and 28 around the upper perimeter of each one of the compartments in the housing 20, and filled with a body of sand adapted to contact with the marginal flanges 29 on the mold bodies 30, are provided for the same purpose just as described in connection with the apparatus of Figs. 1, 2 and 3. The mold cavity 31 and mold body 30 thus forms a continuation of or portion of the interior space in each one of the compartments 20 in the housing 20.

A heater 32, connected to the blower 33, the latter being driven by the drive motor 34, provides a quantity of heated air or similar gaseous medium which is delivered through the conduit 35 extending substantially the entire length of the housing 20. The delivery conduit 35 has a series of outlet manifolds 36 to which the air stream directing nozzles 37 are connected, at each one of the four compartments in the housing 20. Openings are provided between the delivery conduit 35 and each one of the compartments, such openings being adapted to be opened or closed by means of the pivotally mounted damper 38. The damper 38 is in turn operated by means of the damper rod 39 extending out to the exterior of the side wall 21 of the housing 20.

Return conduits 40 extend throughout the length of the housing 20 and are located adjacent each side of the delivery conduit 35. The recirculating or return conduits 40 are joined at the right hand end of the housing 20 by means of the conduit 41 to the conduit 42 returning to the heater 32. The conduits 40 have openings located in each one of the four compartments in the housing 20 which are adapted to be opened or

closed by means of the slideable covers 43 which in turn are manipulated by means of the rods 44 extending through the walls 21 of the housing 20.

From the foregoing description of the apparatus of Figs. 4, 5 and 6, it will be seen that the mold bodies are subjected to the same manner of drying treatment as in the case of the apparatus of Figs. 1 and 2 and that the same advantages, except for an increased production capacity, ensue. In addition, the heated air circulating system may be continuously operated in the apparatus of Figs. 4, 5 and 6, without any material loss of heated air to the atmosphere, and without interruption, as individual mold bodies are placed upon and removed from the supporting housing 20. As completely dried molds are removed from their positions on the housing 20, and new ones, containing green sand, installed in their place, it is merely necessary to close the dampers 39 and outlet opening covers 43 in the particular compartment in which such change-over is taking place.

In Figs. 7, 8 and 9, we have shown the apparatus of our invention, as modified to accommodate the drying treatment of mold parts which do not have an enclosing housing, such as a flask, and do not present any substantial size interior cavities. In other words, the apparatus shown in Figs. 7, 8 and 9 is adapted to accommodate what is commonly called the "core" in foundry practice, and which technically speaking, is the male part of the entire mold body when finally assembled for the casting operation.

In the apparatus of Figs. 7, 8 and 9, there are again the heater 50, the blower 51 and the delivery conduit 52 extending the length of the elongated housing 53. The housing 53 is composed of the bottom wall 54, and the side and end walls 55 and 56, the latter being relatively higher than was found to be the case in the apparatus of Figs. 4, 5 and 6. The housing 53 is divided into individual compartments by means of the transverse walls 57. A plurality of air stream directing nozzles 58 are located in the delivery conduit 52 in each of the compartments of the housing 53 and are adapted to direct the forcibly projected mass of incoming air upwardly and around the exterior surface of the core 59, substantially as indicated by the arrows as shown in Figs. 8 and 9. In addition, there are upper manifolds 60 having outlet nozzles 61, and connected by means of the riser ducts 62 to the main delivery conduit 52, in each one of the compartments in the housing 53. The cores 59 are connected to the channel beams 63 by means of the suspension pins 64. The channel beams 63 are in turn supported upon the compression springs 65 adjacent their outer ends which in turn bear upon the I-beams 66 located adjacent the top and inside the side walls 55 of the housing 53. The top of each of the compartments in the housing 53 is closed by a pair of hinged covers 67, carrying the counterweights 68. The covers 67 have a sealing strip 69, made of asbestos tape or the like, located along their edges adjacent the supporting channels 63, and adapted to form a sealing engagement therewith when the covers are closed and the channels 63 in place. A hinged baffle plate 70 is mounted upon one of the covers 67, being hinged at a point along the outer edge 70 of the latter and is adapted to be drawn over into place when the individual mold core treating compartment is empty, i. e. when the supporting beams 63 are not present.

Return or recirculating ducts 71 extend on each 75

side of the delivery duct 52 and throughout the length of the housing 53. The return ducts 71 are likewise joined by the transverse duct 72 leading to the return intake duct 73 of the heater 50. The inlet openings of the return ducts 71 are located in the horizontal manifold 74 along each side wall 55 of the housing 53 being connected to the return conduit 71 by means of the risers 75, in substantially the same manner and extent as the delivery manifolds 60 and risers 62.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. Apparatus for drying foundry mold bodies 20 of generally concave form, enclosed in a peripheral frame, comprising an open-top housing having an upper marginal edge of substantially the same shape and dimensions as the outer marginal edge of the mold body to be dried and adapted to support the same in inverted position thereon with the mold cavity and parting surface of the mold body exposed in the housing, a heater, an inlet conduit for heated air leading from the heater into the housing, a plurality of nozzles 25 extending upwardly beyond the housing and adapted to direct heated air from the conduit and discharge the air upwardly and outwardly at a plurality of separate locations above the level of the marginal edge of the housing so as to cause such air to impinge in separate spaced streams against the concave surface of the mold body, an exhaust conduit leading from the housing to the heater and opening into the housing below the level of said upper marginal edge, air circulating 30 means to withdraw air from the housing, through said conduit, and force said air through the heater and back into the housing through the inlet conduit and means sealing the joint between the frame of the mold body and the upper marginal 35 edge of the housing.

2. An apparatus according to claim 1 characterized further in that said sealing means comprise an upwardly open channel forming the upper marginal edge of the housing and a body of loose sand substantially filling said channel and adapted to engage the bottom margin of the frame when the mold is supported on the housing.

CHARLES A. BARNETT.
JOSEPH M. BEYVL.
